UNITED STATES PATENT OFFICE.

SAMUEL W. RAPP, OF DETROIT, MICHIGAN.

RADIATOR.

963,807.

Specification of Letters Patent. Patented July 12, 1910.

Application filed June 18, 1909. Serial No. 502,419.

To all whom it may concern:

Be it known that I, SAMUEL W. RAPP, a citizen of the United States of America, residing at Detroit, in the county of Wayne and State of Michigan, have invented certain new and useful Improvements in Radiators, of which the following is a specification, reference being had therein to the accompanying drawings.

- 10 This invention relates to radiators and more particularly to radiators for use upon self-propelled vehicles to cool the water which is circulated through the water jacket of the engine, and its object is to effectually cool the water passing therethrough without retardation of its circulation, and to provide a simple and cheap construction which is not liable to leak, and if injured may be readily repaired.
- 15 To this end the invention consists in so constructing the device that the cooling air may pass freely between and around the members forming the water passages extending between the two tanks to provide a free circulation of water, and which members are formed hollow to provide a central passage in each for air, means being provided to positively draw the air therethrough and these central air passages being continued 20 through the water tanks to assist in cooling the water therein.

The invention also consists in so constructing the members forming the water passages that they are cheap to manufacture, are not liable to injury in ordinary use or to leak, and may be readily repaired if injured.

A further object is to provide a construction embodying other certain new and useful features, all as hereinafter more fully described reference being had to the accompanying drawing in which,

Figure 1 is a front elevation of a device embodying the invention with a portion broken away to show the construction; Fig. 2 is a transverse vertical section through the same; Fig. 3 is a horizontal section substantially upon the line 3—3 of Fig. 2; and Fig. 4 is a perspective detail of the members forming the water and air passages.

50 As shown in the drawings 1 represents a top water tank provided with the ordinary fill opening 2, and 3 is a bottom tank. These tanks are connected by a series of members 4 forming vertically extending water and air passages. Each of these members is formed by an outer wall 5 of thin sheet

metal bent into V-shape in cross section with the longitudinal edges 6 of the metal turned inward, and an inner wall 7 also formed V-shape in cross section with the longitudinal edges 8 of the metal turned outward. These edges 6 and 8 are soldered together thus forming V-shaped tubular members; the space between the walls 5 and 7 forming a water passage. These V-shaped tubular 60 members 4 are secured between the tanks in pairs with the open side of the members forming each pair, adjacent to each other, or the inturned edges 6 in contact with each other, the pairs of members thus forming a 70 diamond shaped hollow member, the space or passage 9 formed by the inner walls 7 of the two members forming an air conduit. The vertical water passages connecting the two tanks are thus formed in two parts consisting of two of the members 4, and by placing them as described, a hollow tubular conduit is formed, the water passing freely downward from the upper tank to the lower tank through spaces between the inner and outer walls of the conduit and air through the passage formed by the inner wall. These hollow members or conduits which are diamond shaped in cross section are secured between the tanks with their longest cross-sectional diameter extending transversely of the tanks and are spaced from one another a short distance to permit the air to pass freely between the same, horizontally through the radiator. A series of diamond 80 shaped openings are provided in the bottom of the upper tank and the top of the lower tank to receive these members with their outer walls 5 soldered in place within the openings so that the water in the upper tank 85 may pass freely into the water space and downward therethrough into the lower tank. The water in the upper tank is prevented from passing into the air passages 9 by a series of elbows 10 which are secured with 90 in the tank 1 with their lower ends projecting into and soldered within the upper ends of the air passages and their opposite ends soldered within a series of openings 11 in the front wall 12 of the tank.

The inner wall 7 forming each air passage 9 is extended beyond the lower end of the wall 5, extending through the bottom of the lower water tank 3 and soldered into openings in said bottom to prevent the water from entering the air passages at their lower ends and to form a continuation of the air

passages downward through the lower tank, upon the bottom of which is formed an air chamber 13 into which each of the air passages open. A pipe 14 is connected to the 5 air chamber 13 at its rear side intermediate its ends and extends upward to a casing 15 within which is a suitable suction fan 16. This fan may be driven in any desired manner to suck the air through the tube 14, 10 chamber 13, and the several air passages 9. An inlet pipe 17 opens into the upper tank and an outlet pipe 18 leads from the lower tank. These pipes are connected in the usual manner with the water jacket of an engine to provide a circulation of water 15 through said jacket into the upper tank downward through the several water passages into the lower tank, and out through the pipe 18 to the water jacket. If found 20 desirable a plurality of spaced fin plates 19 may be soldered or otherwise secured to the outer wall 5 of the several tubes. In this construction the upper and lower tanks of the radiator are directly connected 25 by the vertical water passages thus providing a free and unretarded water circulation, and by making each of the conduits hollow or with an internal air passage 9, and continuing this air passage 30 through the upper and lower water tanks, the water is effectually cooled during its circulation as a large radiating area is provided for each tube or conduit. By providing the fan or similar means to forcibly draw the 35 air through the inner air passages the inner walls 7 are quite as effectually cooled by the air as are the outer walls 5 over which the air passes on its way through the radiator between the tubes.

40 The shape and construction of the members 4 forming the conduits or tubes is such that they are not liable to be injured in general use as the points or apexes of the cross-sections of the tubes extend forwardly or 45 toward the front of the radiator and offers strong resistance to being bent, and the several tubes may be very effectually soldered into the tanks to make a rigid structure which is not liable to become loosened in its 50 joints and leak. If one or more of the members 4 should become bent or broken the injured member may be quite readily removed for repair without taking the whole structure apart, especially if the radiator is 55 manufactured without the radiating fins 19.

It is obvious that changes in the minor details of construction may be made without departing from the spirit of the invention, and I therefore do not limit myself to any 60 particular form or construction.

Having thus fully described my invention what I claim is:

65 1. A radiator comprising water tanks having air passages extending therethrough, and a series of water conduits connecting

said tanks each formed V-shape in cross section, said members being secured between said tanks in pairs with the channeled sides of the members of each pair adjacent to each other to form a center air passage extending 70 longitudinally of each pair of said water conduits and connecting the air passages extending through the tanks.

2. A radiator comprising tanks, and a series of water conducting members connecting said tanks each formed of an inner and an outer wall formed V-shaped in cross section and spaced apart, the ends of the walls being connected to form a water passage between the walls, and said members 80 being arranged in pairs with the channeled sides of the members of each pair contacting to form a center air passage between each pair of members.

3. A radiator comprising an upper and a lower tank, a series of water conducting members each formed of an inner and outer wall formed V-shaped in cross section and spaced apart, the longitudinal edges of one wall being turned inward across the space between the walls to close the water passage between and the longitudinal edge of the other wall being turned outward over the inturned edge and secured thereto, and said members being secured between the tanks and connected thereto at their ends and arranged in pairs with the channeled sides of the members of each pair in contact to form the center air passage.

4. A radiator comprising an upper tank, a series of separate and independent curved members within said tank opening at one end through the forward side of the tank and projecting at their opposite end through the bottom of the tank, a bottom tank, a series of water conducting members each formed with a longitudinal channel in one side and said members being arranged in pairs with the channeled sides of the members of each pair in contact to form center air passages into the upper ends of which the lower ends of the curved members project, said water conducting members being secured to said ends, and members extending vertically through the lower tank and forming continuations through the lower tank of the center air passages formed by the channeled sides of the conducting members.

5. A radiator comprising an upper water tank, a series of elbows in said tank spaced apart and opening at one end through the front of the tank and at their opposite ends through the bottom of the tank, the lower water tank having a series of holes in its top and bottom, a series of water conducting members each formed of an outer sheet metal wall bent channel shape in cross section with the longitudinal edges of the metal turned inward, and an inner wall formed channel

shaped in cross section with its longitudinal edges turned outward and secured to the in-turned edges of the outer wall to space the two walls apart, these water conduits being 5 arranged in pairs with their channeled sides in contact to form a center air passage between and secured at their ends to the tanks, the outer walls of the members being secured within the opening in the top of the lower 10 tank, and the inner walls of said members being extended beyond the outer walls

through the lower tank and secured in the openings in the bottom of said tank, and the lower ends of the elbows being secured within the center air passages formed between 15 the pairs of members.

In testimony whereof I affix my signature in presence of two witnesses.

SAMUEL W. RAPP.
